UNITED STATES PATENT OFFICE.

WILLIAM JOSEPH ANDERSON, OF HYDE, ENGLAND.

SHOWCARD, CALENDAR, AND THE LIKE.

1,421,367.

Specification of Letters Patent.

Patented July 4, 1922.

Application filed May 19, 1919. Serial No. 298,321.

To all whom it may concern:

Be it known that I, WILLIAM JOSEPH ANDERSON, a subject of the King of England, residing at 1 Meadow Avenue, Hyde, 5 in the county of Chester, England, have invented certain new and useful Improvements Connected with Showcards, Calendars, and the like, of which the following is a specification.

10 This invention relates to show-cards, calendars, or the like.

A show card, calendar, or the like, according to my invention, essentially comprises a head-piece portion which represents 15 a show-card or permanent advertising medium; a "perishable" depending or hanging apron-like refill portion; a lath secured to the upper end of said apron-like portion; and means associated with said head-piece 20 portion whereby the lath of which said apron-like portion is detachably secured thereto.

I will further describe my invention with the aid of the accompanying sheet of explanatory drawings from which it will readily be seen that a head-piece and apron-like refill are so constructed that it is quite 25 a simple matter to detach an old refill when stripped of its goods, or—as in the case of a 30 calendar—when out of date, and substitute a new one.

In said drawings, like characters of reference denote like or equivalent parts wherever they occur.

35 Figs. 1 to 3, inclusive, illustrate one mode of embodying my invention, Fig. 1 being a view of a head-piece or permanent body part, Fig. 2 a view of a "perishable" refill, and Fig. 3 a view showing the refill attached 40 to and depending from the head-piece portion.

a indicates a permanent head-piece or body portion representing a show-card, in which are formed apertures or slots *b*. *c* 45 denotes an apron-like refill at the upper end whereof is secured a lath *d* which is of such length that its ends may be inserted through said apertures *b* of head-piece *a*; thus said refill is detachably hung from the head-piece.

Figs. 4, 5, and 6 illustrate a modification, Fig. 4 showing a permanent head-piece, Fig. 5 a refill, and Fig. 6 the head-piece and refill assembled together.

55 In this modification an elongated slot *b*¹ is formed in the permanent head-piece *a*,

and the ends of a lath *d* secured to the upper portion of the refill, by abutment against the rear face of said head-piece, sustain the refill in its hanging or depending position. 60

Fig. 7 illustrates in front and side view a modified construction, in which a lath *d*¹ is secured by means of fasteners *e*, say of "paper-fastener" type, to the rear of a head-piece *a*, and a lath *d* secured to a refill *c* 65 rests upon the top of lath *d*¹.

Fig. 8 illustrates in front and side view a modified construction, wherein a hinged shutter *a*¹ is created by punching the head-piece in such a manner, that a frame-work *a* is left. Lath *d* of refill *c* is supported on the lower member of the frame *a*. Said hinged shutter forms the main space for the necessary advertising matter and when in use slightly protrudes or inclines outwardly through resting on the upper portion of refill, thus accentuating the advertising matter. 75

Fig. 9 illustrates in front view and section a modified construction wherein a frame *e* 80 is secured to the rear of a head-piece *a*, lath *d* of refill *c* being positioned in the lower member of frame *e*.

Fig. 10 illustrates in front and side view a modified construction which is similar to 85 that shown in Figs. 4 to 6, with the exception that hinges *f* are formed in the head-piece *a* in alignment with slot *b*¹, in order to strengthen the head-piece at this part and ensure that the refill *c* shall hang perpendicularly. 90

Fig. 11 illustrates in front and side view an addition of a strut which in combination with Figs. 6, 8, and 10 permit of the head-piece, partaking of a standing upright show-card and the apron revolving on its lath in slot, to take if desired the form of an outward inclined plane, as shown in dotted lines, thus creating an effective display, similar to a box of goods with raised lean-back 100 lid: A very desirable thing, encouraging window-display. Fig. 12 illustrates in front and end view a modified construction wherein two up-turned prongs *h* secured to head-piece *a* support lath *d* of the depending refill *c*. 105

Having now described my invention, what I claim as new and desire to secure by Letters Patent is:—

A show device comprising a head piece 110 portion having a slot approximately the length thereof leaving comparatively nar-

row portions that may be flexed more readily than other portions of said head piece, a perishable apron-like refill portion having an upper edge of a length less than the 5 length of the head piece slot and adapted to be supported entirely and wholly in the same plane as that of said head piece, and a lath secured to the front face of said apron-like portion at the upper end thereof 10 and of a greater length than said apron-

like portion so that the lath ends may extend into the slot of said head piece portion and support said apron-like portion.

In testimony whereof I affix my signature in the presence of two witnesses.

WILLIAM JOSEPH ANDERSON.

Witnesses:

JOHN WILLIAM THOMAS.
